UNITED STATES PATENT OFFICE.

JULIEN CAYROL, OF PARIS, FRANCE.

INCANDESCENT GAS-BURNER.

1,249,326.

Specification of Letters Patent. Patented Dec. 11, 1917.

Application filed April 26, 1917. Serial No. 164,702.

To all whom it may concern:

Be it known that I, JULIEN CAYROL, citizen of the French Republic, residing at Paris, 114 Rue de Grenelle, France, have 5 invented new and useful Improvements in Incandescent Gas-Burners, of which the following is a specification.

My invention has for its object an improved burner for incandescent gas lighting. 10 The particular object of my invention is to so construct the burner that the volume of the gas may be regulated independently from the pressure in the gas supply pipe, a means also being provided controlled by the 15 pressure of the gas.

My invention is shown on the accompanying drawing: in which,

Figure 1 is a sectional elevation of my burner, the section being taken through the 20 axis of the burner.

Fig. 2 is a sectional plan, the section being on the line II—II in Fig. 1.

Figs. 3 and 4 show respectively in elevation and plan, on a larger scale, the special 25 means for obstructing the passage of the gas.

The means for regulating the flow of the gas comprises a nozzle *a* which is threaded into the sleeve *b* formed at the bottom of the chamber *c* where air is admitted through the 30 slots *d*, to mingle with the gas rising in the mixing tube *e*. The nozzle *a* contains within its lower end *a*¹ the regulating means.

A valve contained in the nozzle *a* can be displaced therein by means of inclined 35 screws *f*. This valve comprises a cylindrical body *g* having vertical grooves *g*¹ and provided at its lower end with a collar *g*² on which bears a helical spring *h* the upper extremity of which bears against a shoulder *a*² 40 in the nozzle *a*. The latter is closed at its upper end by a cover *i*, having a central aperture *i*¹, through which the gas is admitted to the chamber *c*. This aperture *i*¹ can be partially or wholly closed by the conical 45 head *g*³ of the valve *g* as the latter is raised or lowered by means of the screws *f*.

When the screws *f* are completely withdrawn into the wall of the nozzle *a*, the valve *g* will descend by gravity, assisted by

the spring *h*, against an arresting abutment *j*.

Should the central aperture *i*¹ become clogged, the screws *f* can be manipulated in such a manner so as to force the extremity of the conical head of the valve *g* repeatedly 55 into the said aperture thus effectively cleansing it.

Into the lower end of the nozzle *a*, is screwed a connecting piece *k* which, in turn, can be screwed onto the gas supply pipe. 60 This piece *k* carries a horizontal partition *m* provided with perforations *n*. The partition *m* carries a vertical stem *o* adapted to guide the valve represented in detail in Figs. 65 3 and 4. This valve comprises a disk *p* formed on the lower extremity of a socket *q*, the upper end of which forms a pointed arch and is provided in its center with an orifice *r*. According to the pressure of gas, the 70 valve *p*, *q* will be more or less raised, and thus project more or less into the tubular part *k*¹ of the member *k*, thus regulating the flow of the gas.

I claim as my invention:

In an incandescent gas burner, the combination with a loose plug valve controlling the orifice in said burner, and means for raising the plug valve to more or less project into said orifice, of a connecting piece having a neck portion screwed into the lower 75 part of the burner and a perforated horizontal partition, a central vertical stem projecting upwardly therefrom, a socket loosely guided on said stem and having an orifice in its upper extremity and carrying at its 80 lower end a disk extending over the perforations in said horizontal partition, the socket under the pressure of the gas being raised, to project more or less into the neck portion of the said connecting piece. 85 90

In testimony whereof I have signed my name to this specification in the presence of two subscribing witnesses.

JULIEN CAYROL.

Witnesses:

HENRI MONIN,
CHAS. P. PRESSLY.
